ALONZO SKINNER, OF WARREN, ASSIGNOR TO LUCIUS A. SKINNER,
OF WEST NOVI, MICHIGAN.

Letters Patent No. 88,090, dated March 23, 1869.

IMPROVEMENT IN SUSPENDED PORTABLE FENCE.

The Schedule referred to in these Letters Patent and making part of the same

To whom it may concern:

Be it known that I, ALONZO SKINNER, of Warren, in the county of Macomb, and State of Michigan, have invented a new and useful Improvement in Suspended Portable Fence; and I do declare that the following is a true and accurate description thereof, reference being had to the accompanying drawings, and to the letters of reference marked thereon, and being a part of this specification.

Figure 1 is a perspective view of my invention.

Figure 2 is an elevation of the gallows-frame.

Like letters indicate like parts in each figure.

The nature of this invention relates to an improvement in the construction of portable fences, so that they are not only securely sustained in a vertical position, but are suspended in the air above the ground, requiring no posts to be set in the ground, and made in sections, so that the same may be set up anywhere, easily removed, and economical to build.

The invention consists in sustaining and suspending lengths of board fence, constructed in the ordinary way, upon suitable gallows-frames, notches being cut in the

top thereof, by means of which the fence is held in position.

A, in the drawings, represents a length of board fence, constructed of vertical slats B, and horizontal bars of boards C, nailed together in the usual way.

D are short pieces of plank, from each end of which rise the diagonal braces E, projecting upward and inward, until they meet at a common centre, as at F, where the notch G is cut, as shown in the drawings, thereby completing the gallows-frame.

The bar 3 being the third one from the bottom, and the next one to the top, is set edgewise into said notches G, in a series of gallows-frames, as described.

What I claim as my invention, and desire to secure by Letters Patent, is—

The gallows-frame, composed of the parts D and E, in combination with board fence A, when constructed and arranged substantially as herein described.

ALONZO SKINNER.
